UNITED STATES PATENT OFFICE.

JOSEPH KAISER, OF KATALLA, DISTRICT OF ALASKA.

DESIGN FOR A SUPPORTING-BRACKET.

No. 39,572.

Specification for Design.

Patented Sept. 22, 1908.

Application filed May 1, 1908. Serial No. 430,406. Term of patent 14 years.

To all whom it may concern:

Be it known that I, JOSEPH KAISER, a citizen of the United States, residing at Katalla, in the District of Alaska, have invented a new, original, and ornamental Design for a Supporting-Bracket, of which the following is a specification, reference being had to the accompanying drawing, forming a part thereof.

The figure is a side elevation of a bracket, showing my new design.

I claim:

The ornamental design for a supporting bracket as shown.

JOSEPH KAISER.
